PUMP ROD CONNECTING DEVICE

Elmer R. Thomas, Healdton, Okla., and Harry L. Ayers, Wichita Falls, Tex.; said Ayers assignor to said Thomas

Application December 2, 1947, Serial No. 789,188

10 Claims. (Cl. 74—593)

1

This invention relates to improvements in pump rod connecting devices, and more particularly to devices which automatically hook-on and hook-off rod lines of pumping wells.

In the pumping of oil wells and the like from a central source of power, the pumping usually is done by a mechanism, such as a crank or an eccentric, that imparts a reciprocating movement to a rod line and which crank or eccentric is driven by an engine or a motor through speed reducing gearing. The power source usually is so positioned that certain wells are attached to one side of the crank or eccentric by means of their respective rod lines, and others to the opposite side of the crank or eccentric in order substantially to balance the load so that the engine or motor has only to overcome the friction and to lift the actual weight of the fluid being pumped.

Wells being pumped have different capacities of production, and require pumping at various times for periods of varying duration in order to obtain the maximum production and the maximum efficiency. To prevent undue wear on the equipment when the wells have been "pumped off," it has been necessary heretofore, to have an operator or pumper on duty all of the time, so that when necessary, he could connect the wells to or disconnect them from the source of power, according to a pre-arranged schedule or in accordance with the physical properties of the various wells as to production, or, when a well ceases to produce fluid, to "hook the well on" after sufficient fluid has filled the reservoir around and adjacent the working barrel or pump in the bottom of the well. One pumper frequently must be responsible for the care of several (sometimes as many as twenty) wells, as well as the other duties incident to the care of oil producing property. Consequently, it has not always been possible for him to "hook-on" or "hook-off" a well at the proper time for the most efficient performance or to save unnecessary wear and tear on equipment, or to make needed repairs and replacements.

The primary object of this invention is to provide a mechanism that will "hook-on" a rod line of a well with a source of power, at a predetermined time, and to pump the well for a predetermined period of time, which times can be determined by the number of strokes per hour at which the eccentric or crank is timed to operate.

Another object of this invention is to provide a mechanism that can be set to "hook-off" a well automatically for a predetermined period of time, and the automatic "hook-on," pump, and "hook-off" cycle can be repeated indefinitely, or can be reset to operate on a different cycle for any or all of the time factors.

Still another object of this invention is to provide a mechanism that is so carefully balanced

with the associated parts and the hook-off and hook-on mechanism that the "pounding" action heretofore encountered in pumping wells, when they become "pumped off," will cause the rod line to be disconnected by the "hook off" mechanism even though the pumping cycle has not been completed.

Yet another object of this invention is to provide a mechanism that will make possible the replacing or repairing of sections of rod lines without auxiliary pulling implements and without serious danger to workmen.

In the present invention, the human factor very largely has been eliminated, by the provision of an automatic "hook-on" and "hook-off" mechanism. This promotes efficiency, and curtails injury to the workmen.

Due to the particular balance of the parts associated with the "hook-on" and "hook-off" mechanism and to the peculiar characteristics of pumping wells giving a pounding action when the plunger of the pump "hits the fluid" when a well is pumped off or has only a few inches of fluid left in the bottom of the working barrel and the working barrel plunger travels all the way down and hits the fluid at a low level in the working barrel, it will cause a slackening of the rod line which will cause the rod line to loosen sufficiently to allow the "hook-on" pin to loosen and "hook-off" the rod line, even though the pumping cycle is not complete; however, at a pre-arranged time, the mechanism will reconnect the rod line to resume the pumping operation.

Occasionally, rod lines break and require repair or replacement. By removing the broken pull rod from the rod line, it can be replaced by a new one which has necessitated heretofore the use of "come alongs" or jacks to loosen or take the slack out of the rod line, so that it may be disconnected or reconnected with the power source before the pumping operation may be resumed.

With the present invention provision is made to disconnect or reconnect the loose rod line, and, by the proper manipulation of the various parts, the rod line may be disconnected for repair or may be reconnected or tightened sufficiently so that it may be operated by the crank or eccentric mechanism.

An embodiment of this invention is illustrated in the accompanying drawings, in which:

Fig. 1 is a side elevation of the mechanism with the center portion broken away;

Fig. 2 is a top plan view of the mechanism, as shown in Fig. 1;

Fig. 3 is a side elevation of a "hook-off" or "hook-on" pin mechanism in position to receive the rod line for "hook-on" or for sustaining the weight of the rod line;

Fig. 4 is a similar view thereof after the weight of the rod line has engaged the pin to actuate the mechanism;

Fig. 5 is a perspective view of the rod line "hook-on" or "hook-off" pin removed from the mechanism;

Fig. 6 is a top plan view of the "hook-on" or "hook-off" mechanism but with the pin in raised position;

Fig. 7 is a side elevation of the mechanism with the pin in raised position substantially as shown in Fig. 6;

Fig. 8 is a vertical longitudinal section taken on the line 8—8 of Fig. 6;

Fig. 9 is a perspective view, with parts broken away and shortened and other parts removed, of the rod line "hook-on" and "hook-off" stirrups;

Fig. 10 is a perspective view of the timing mechanism of the device and associated parts;

Fig. 11 is a cross section taken on the line 11—11 of Fig. 2, showing the clutch arrangement of the timing device;

Fig. 12 is a perspective view of a portion of the frame showing the guide rollers thereon;

Fig. 13 is a top plan view of the latch operating mechanism with parts broken away and in section and with the dashed outline showing the mechanism in tripped position; and

Fig. 14 is a side elevation thereof.

With more detailed reference to the drawings, the numerals 1—1' designate suitable supports, such as posts which may be embedded in the ground or in concrete and upon which a frame is supported. The frame 2 includes members which may be of any suitable material, such as structural steel, angle iron, or the like, and are secured to the posts 1—1' by bolts 3. A cross member 4 ties the frame members 2 together and is secured thereto, while additional connections may be provided if desired.

Brackets 5 are secured to the frame members 2 and have rollers 6, journaled thereon (Figs. 2 and 12) for supporting and guiding the rods of the mechanism as will be described more fully hereinafter. Additional guide rollers are shown at 7, for the rods and stirrups.

A stirrup 8 at the power end, comprises parallel rods or legs 8', having spaced webs 10 and 11 secured therebetween to form openings or eyes therethrough, and a loop end 12 which, with the webs 10 and 11 and loop end 12, are adapted for engagement with the "hook-on" and "hook-off" pin of the mechanism. The legs 8' are parallel with connecting rods 13, and the rods 8' project through and are slidably in a clamp 14 which clamp connects together the inner ends of the rods 13. This clamp 14 is formed by members secured by bolting in binding engagement with the rods 13 but which will permit free sliding movement of the stirrup 8 with respect to the clamp 14.

The connecting rods 13 extend outwardly from the clamp 14, and their outer ends are secured in binding relation by a clamp 15, including members bolted together and which clamp the ends of the rods 13 fixed with respect thereto. A power line stirrup 16 includes parallel rods 17 secured together by a clamp 18 which clamps the ends of the rods 17 in binding engagement, and which clamp 18 also extends in guiding engagement with rods 13, slidably receiving the latter. The parallel rods 17 have a series of cross webs 19, 20 and 21 secured therebetween for engagement

with a "hook-off" pin of the mechanism, as will be more fully described hereinafter.

The parallel legs 17 of the stirrup 16 extend outward through the clamp 15 and are freely slidably therein. The rods 17 are joined by a closed loop at the outer end of the stirrup 16. The clamp 15 has the midportion thereof cut-away at 22 to receive the rods 17, and these have fixed therebetween a cross bar 23, slidable through the recess 22, as shown in Fig. 9. A pin 25 is inserted through a hole in the clamp 15 and through the hole 24 in the bar 23, when centered with the clamp hole, so as to lock the stirrup 16 and the clamp 15 together for unitary movement of the stirrup and connecting rods 13, during the pumping operation. The stirrup 16 is connected with an end 26 of the rod line.

However, when the rod line becomes disconnected, as by the rods breaking, or when, for any other reason, it is necessary to let out the slack in the rod line 26, the pin 25 is removed so as to permit the stirrup 16 to slide outward. Then, after the rod line has been repaired or it is desired to tighten the rod line, the pick-up mechanism is operated as will be more fully described hereinafter.

Spaced apart and mounted near each end of the frame 2 are "hook-off" and "hook-on" devices, generally designated as 27 and 28, respectively, each of which forms a latch connection with one of the stirrups 8 or 16. These devices are identical in structure and like reference characters will designate like parts on the two devices, except the numerals designating the various parts of the "hook-on" device 28, will be primed (').

The "hook-off" device 27 (Figs. 3 to 8) comprises a base 29 which is secured to the cross member 4 by bolts 30. This structure has sufficient strength so that it will not yield as a result of the weight of the rods 26 being applied thereto when the rods are "hooked-off." The base 29 has a pair of upstanding ribs 31 thereon, between which a central bifurcated lever 32 is mounted. The lever 32 is pivoted at 33 to the upstanding ribs 31, and has a "hook-off" pin 34 pivotally connected thereto by a bolt 35. A bifurcated end 36 is integral with "hook-off" pin 34 and extends upward at an obtuse angle thereto. The end 36 is connected with links 37 by a pin 38 passing through slots 39 in the links 37.

The opposite ends of links 37 are pivotally connected together by a pin 40. The pin 40 also pivotally connects together levers 41 and links 42, and extends through a slot 43 in a link 44 to limit the travel of the pin 40. The levers 41 are secured rigidly, as by set screws, to a shaft 45 that extends laterally of the device and to which an operating arm 46 is also secured. The shaft 45 is journaled in the upstanding ribs 31 to permit the levers 41 to swing about the axis of the shaft 45.

The links 42 have the upper ends thereof pivotally connected by a pin 47 to counterweight lever 48. The lever 48 is mounted between the bifurcated portions of up-turned ends of the lever 32. A pin 49 connects together the upper end of the lever 32 and the end of the lever 48. The lever 48 has a weight 50 adjustably mounted thereon for adjustment along the length thereof and secured thereto by a set screw 51, which weight gives the proper counterbalance to the pin 34.

The link 44 is pivoted on a bolt 52, which bolt 52 is carried by the upstanding ribs 31. With the device, as shown in Fig. 7, the pin 34 is in

raised position, and it is now so positioned with respect to the pivot centers 38, 40, 47, 49, that the weight 50 overbalances the pin and keeps this pin in raised position. However, by shifting the arm 46 to the opposite side, as shown in Fig. 3, the pin 34 is dropped into an inclined position forward, but since the pivot point 40 has shifted to the opposite side of the dead center position between the pivot points 45 and 47, as shown in Fig. 3, the pin 34 is so shifted with respect to the fulcrum points that the pin 34 overbalances the weight 50 and the device will remain in this position until positively moved by the stirrup into the position shown in the lower portion of Fig. 1, and also in Fig. 4.

The positive swinging movement of the pin 34 by the stirrup acts through the links 37 to shaft the toggle 41—42 to its opposite position, with the fulcrum points back in substantially the same relative positions as shown in Fig. 7, except that the pin 34 is being held in binding engagement against transverse supporting member by the weight of the rods 26, which are attached to the pump jack of the well.

The "hook-on" device 28 is operated in like manner. As the pin 34 of the device 27 engages the supporting member 4, the rod 7 which is attached to the crank or eccentric of the power unit, will move outward, which will relieve the pin 34' of frictional contact and since the "hook-on" device 28 has the fulcrum points shifted in positions substantially as shown in Fig. 4, the weight 50' will overbalance the weight of pin 34', so as to lift the pin 34', and it will assume the position as shown in the upper portion of Fig. 1, thereby disconnecting the rod line to the well.

It will be evident that during pumping of the well, the power motion is transmitted from the power line 7, through the stirrup 8, the latch pin 34', and clamp 14 to the connecting rods 13 to reciprocate said connecting rods, as shown at the top in Fig. 2. The opposite ends of the connecting rods 13 transmit motion through the clamp 15, pin 25, bar 23, and stirrup 16, to the pump rod line 26. The heads on the outer ends of the connecting rods 13 limit the outward movement of the clamps 14 and 15 with respect thereto.

During this pumping action, the "hook-off" pin 34 is disengaged from the stirrup 16, as shown in Fig. 7. However, upon engagement of the "hook-off" pin 34, as shown in Fig. 1, this will lock the stirrup 16 in a holding position, while the stirrup 8 will reciprocate with respect thereto, its "hook-on" pin 34', then being released, as shown in Fig. 1.

Mounted at the forward end of the frame 2 is a power take-off mechanism comprising a lever 61, which is attached to a shaft 62. The shaft 62 is connected with an over-running clutch, generally designated at 63, connected thereto, and the over-running clutch 63 has a gear 64 connected therewith to be driven thereby. The shaft 62 is journaled in a bearing 65 so that the lever 61 will protrude downward between arms 66 and 67. The arm 66 is adjustably attached to the inner end of the stirrup 8 for adjustment lengthwise thereof and the arm 67 is adjustably secured to the arm 66. The lever 61 is positioned between the outturned portions of the arms 66 and 67 (see Fig. 10), so that upon reciprocation of the rod 7 and the stirrup 8, a rocking motion is imparted to the lever 61, which in turn rotates the shaft 62 through an arcuate movement. In so doing,

the rollers 63a alternately disengage and engage cam faces 63b (Fig. 11), so as to rotate the gear 64 in one direction step-by-step.

This gear 64 in turn rotates a large gear 68 which is secured to a shaft 69 in mesh therewith. The shaft 69 is journaled in bearings 70 and has a sprocket wheel 71 secured thereto for turning movement therewith upon the turning of the gear 68. A chain 72 passes around sprocket wheel 71 and around sprocket wheel 73. The chain 72 is of the type that has removable pins at the joints of the links, which pins may be removed and pins 74 and 75 substituted therefor selectively. The pins 74 and 75 protrude inward and outward, respectively from the chain 72, as shown in Fig. 2.

The pins 74 are adapted to engage the arm 46, while the pins 75 are adapted to engage an arm 76 (Figs. 13 and 14) which is pivotally attached to a cover 77 by a pin 77'. The arm 76 has a weight 78 on an outwardly extending angular portion 79 thereof. The arm 76 has a link 80 attached thereto, which link 80 is also attached to a link 81. The link 81 is attached to a slidable member 82 intermediate the ends thereof, by a pivot bolt 83. A link 84 is pivotally secured to the upper portion of the cover 77 by a pivot bolt 85 at one end, and a pivot bolt 86 at the other end of the link 84 with the outer end of the slid-able member 82.

The purpose of this linkage arrangement is to move the outstanding finger 87 of the slidable member 82 into and out of operating position relative to the cover 77, so that it will disappear within the confines of the outturned portion of the cover 77 when the lever 76 is in a retracted position, as shown in full outline in Figs. 13 and 14. The outstanding finger portion 87 will move transversely outward and longitudinally along the upper edge of the cover 77 when the lever 76 is moved by the pin 75, which pin will move the lever 76 from the position as indicated in full outline in Figs. 13 and 14, to the position shown in dotted lines therein. In so doing, the project-ing finger will move transversely outward and longitudinally along the inner edge of the cover 77, and engages an arm 46', mounted on the shaft 45'. In so doing, the finger 87 will move the arm 46' from the position indicated in Fig. 1 to a position substantially like that shown in Fig. 3.

Then, upon outward movement of the stirrup 8, the pin 34', which is positioned outward and at an angle, as in Fig. 3, will be engaged by a web 10 to bring the pin 34' into binding engagement with the clamp 14. Since the clamp 14 is in binding engagement with the rods 13, the rods 13, clamp 14, and stirrup 8 will move in unison. However, as soon as the finger 87 has moved the arm 46' to move the mechanism into the position shown in Fig. 3, the pin 75 will pass over the end of lever 76, as indicated by the dash outline of the chain 72 in Fig. 14, and the weight 78 will cause the lever 76 to return to the position as indicated in full outline in Fig. 14.

When it is returned to this position the finger 87 is refracted and will permit freedom of movement of the arm 46' along the side of the cover 77, so it may return to the position as shown in Fig. 4, when the web 10 of the stirrup 8 engages the pin 34', which engagement shifts the pin 34' from the position shown in Fig. 3 to that shown in Fig. 4, and likewise, shifts the pivot points to the position shown in Fig. 4. However, the movement of the pin 34' upward is restrained by the frictional engagement of the web 10 and the clamp 14, and, on the inward movement of the

stirrup 8 and rods 13, the bar 21 will be moved inward. This will loosen the frictional hold on the pin 34 of the device 27, and since the hook-off mechanism 28 is in the position substantially as shown in Fig. 4, the weight 50 overbalances the pin 34 and lifts it into the position shown in Fig. 7, upon "hooking-off" at the rod line 26, to stop the pumping of the well.

The timing of the device is accomplished by inserting a hook-off pin 74 and a hook-on pin 75 in the chain 72 at predetermined intervals and positions, and with the chain 72 geared to travel a given lineal distance in a given length of time. The pumping operation of the well can be so timed according to the number of pumping actions per minute, that the well may be made to pump any desired length of time, as for instance, from fifteen to twenty-four hours, and "hooked-off" for any length of time, as from fifteen to twenty-four hours, considering the chain 72 to have made a complete cycle in twenty-four hours.

As a result of the operation of pull rod lines on oil producing properties, these pull rod lines occasionally break or become separated, which allows the plunger rods of the well to drop. Since the weight of the pump plunger rods may be several thousand pounds, it is necessary, in order to repair or replace pull rods, to disconnect the pull rods from the power unit to relieve the pull rods of the weight of the plunger rods. When the repairs have been made, it is necessary to tighten the lines leading to the pump jack and to reconnect these to the source of power.

With the present invention, the slackness in the rod line may be taken up or let out without the use of jacks or other type of winch mechanism.

When the rod line 26 breaks or becomes disconnected, the rod line will have to be slackened by disconnecting the pins 34 and 34', at which time the rod line may be repaired or a new rod used to replace the broken rod. Upon disconnecting the pins 34 and 34' from the stirrups 16 and 8, respectively, the stirrup 16 and rods 13 are moved outwardly by the weight of the attached plunger rods. It is now necessary to pick up or retighten the rod line 26 in the following manner:

After the repair has been made, and the stirrup 16 is extended outward to the furthest limit, by the pin 34 of the device 27 being raised to the position substantially as shown in Fig. 7, and with the rods 13 disconnected from the device 28 by raising the pin 34' to the position as shown in Fig. 7; sufficient slack will be permitted in the rod line to make possible the repair or replacement and reconnection of the rod line 26. After the repair has been made, the pins 34 and 34' of the devices 27 and 28 are dropped into the cocked positions as shown in Fig. 3. With these pins so positioned, and with the rod line 7 and stirrup 8 moving inward relative to the rods 13, the pin 34' will engage loop 12 so as to draw the rods 13 and stirrup 16 inward. The pin 34 will ride over the web 19, and on outward movement of the rods 26 the pin 34 will engage the web 19 and suspend the weight of the rods 26 against the cross member 4 which will arrest the outward movement of the rods 13. With the movement of these rods arrested, and with the stirrup 8 slideable within the clamp 14, upon the outward stroke of the rod 7, the pin 34' will ride over the web 11, at which time the rod 7 will reverse its direction and move inward. In so doing the web 11 will bring the pin 34' into

binding engagement with the outer face of the clamp 14, which will move the clamp 14 and the rods 13 inward a sufficient distance to cause the pin 34 of the device 27 to ride over the web 20, at which time the rod 7 again will reverse its travel and permit the rods 13 and stirrup 16 to move outward, causing the web 20 to engage with the pin 34 and move the pin into binding engagement with the inner face of the transverse clamp 4.

Upon reversal or outward movement of the rods 13, these will be engaged and held by the pin 34 against outward movement, and the rod 7 and stirrup 8 moves outward and slidably through the clamp 14, which will permit the pin 34' to ride over the web 10, shown in Fig. 2. Upon the movement of the pin 34' over this web 10, the rod 7 will reverse its movement and start to move inward. In so doing, the web 10 will engage the pin 34' and move it into binding engagement with the clamp 14. Then upon continued inward movement of the rod 7 and stirrup 8, the clamp 14 and rods 13 will be drawn inward until the pin 34 of the device 27 will ride over the web 21, substantially as shown in Fig. 2. At that time, the rod 7 will reverse its movement and start to move inward. At this point the well has been picked up and the rods put into operation substantially as has been described hereinbefore. The pumping will continue until such time as the pin 74 engages the arm 46, causing the pin 34 to be lifted first to the position shown in Fig. 3, and then to the position shown in Fig. 7 for "hooking-off" the rod line as above described.

Each time the stirrup 16 moves outward causing one of the webs 19, 20 or 21 to engage the pin 34 in the position as shown in Fig. 3, and move it into the position shown in Fig. 4, and the arm 46 is moved from the position as shown in Fig. 3, to that shown in Fig. 4, the linkages and center of the toggle 41 and 42 are shifted so that the pin 34 would be lifted upon the slackening of the web 19, 20 or 21 from frictional contact with pin 34. Therefore, the arm 46 has to be returned from the position as shown in Fig. 4 to the position as shown in Fig. 3, each time after the weight is released from against the pin 34, so that the pin 34 will ride over the bars properly during the successive steps used in picking up the rod line 26. Likewise, the arm 46' has to be returned from the position substantially as shown in Fig. 4, to that shown in Fig. 3, each time after the weight is released from the pin 34' from the loop 12 or webs 10 and 11, so as to shift the linkages to permit the pin 34 to ride over one of the bars and to shift the toggle center of the linkage device 28, substantially as described for the mechanism 27. By the reversal of the above steps, the rod line 26 may be "let out" or slackened for repair, etc.

The entire unit may be provided, if desired, with a cover thereover, to protect the operating parts from the weather.

The invention has been described primarily as to the automatic operation thereof; however, it is to be understood that by the manual operation of the arms 46 and 46', the rod line 26 may be hooked off or hooked on by the respective operations. The picking up of the rod line may be done by manually operating the arms 46 and 46' as described above or the weight 50 may be moved inward toward the fulcrum point until the operation is accomplished, after which time the weight may be reset to the correct point so that

the lever 48 or 48' may raise the pin 34 or pin 34' automatically upon releasing of the weight and friction contact with members 4 and 14 respectively.

While the invention has been illustrated in one embodiment, it is recognized that variations and changes may be made therein, without departing from the invention, except as specified in the claims.

We claim:

1. In a pump rod connecting device, the combination of power and pump rod sections, a connecting section, and a toggle action slide bolt latch device for connecting one of the power and pump rod sections with the connecting section, after a predetermined number of strokes of the power section.

2. In a pump rod connecting device, the combination of power and pump rod sections, a connecting section, and toggle action slide bolt latch means for connecting one of the power and pump rod sections with the connecting section, after a predetermined number of strokes of the power section.

3. In a pump rod connecting device, the combination of power and pump rod sections, a connecting section, and toggle action slide bolt latch means for attaching the connecting section with one of the power and pump rod sections and constructed for connection during operation of the power section, after a predetermined number of strokes of the power section.

4. In a pump rod connecting device, the combination of power and pump rod sections, a connecting section, means for anchoring the pump rod section during reciprocating movement of the power section relative thereto, and weight actuated toggle action slide bolt latch means for attaching the connecting section with the power section during operation of the power section, after a predetermined number of strokes of the power section.

5. In a pump rod connecting device, the combination of power and pump rod sections, a connecting section, means for anchoring the pump rod section during reciprocating movement of the power section relative thereto, and latch means for attaching the connecting section with the power section during operation of the power section, said power section having cross members connected therewith, a trip means comprising a pair of pivoted levers connected together and interconnected with a pivoted latch bolt so as to engage said cross members step-by-step and to be locked therewith automatically during operation of the power section.

6. In a pump rod connecting device, the combination of power and pump rod stirrups, each having spaced rods with longitudinally spaced connecting webs therebetween, a connecting section including spaced rods slidably mounted relative to the power stirrup, means for connecting said rods with the pump rod stirrup, a latch device for each of the stirrups including trip means and a pin connected therewith, said pin being in position to ride over and successively engage step-by-step the webs, and means for locking the pin in engagement with one of the webs.

7. In a pump rod connecting device, the combination of power and pump rod stirrups, each having spaced rods with longitudinally spaced connecting webs therebetween, a connecting section including spaced rods slidably mounted relative to the power stirrup, means for connecting said rods with the pump rod stirrup, a latch de-

vice for each of the stirrups including trip means and a pin connected therewith, said pin being in position to ride over and successively engage step-by-step the webs, and means for locking the pin in engagement with one of the webs, the latch device for the pump rod stirrup having the pin arranged to lock said stirrup in holding position while the latch device for the power stirrup is released and the connecting means is disconnected.

8. In a pump rod connecting device, the combination of an endless chain timing device having timing lugs thereon for the connection of power and pump rod sections, each having a rod, longitudinally spaced cross members thereon, a connecting section including a rod slidably mounted relative to the power member, a latch device for each of the power and pump rod members and including trip means and a pin connected therewith for actuation by said endless chain timing device, and means for locking the pin in engagement with one of the cross members.

9. In a pump rod connecting device, the combination of an endless chain timing device having timing lugs thereon for the connection of power and pump rod sections, each having a rod, longitudinally spaced cross members thereon, a connecting section including a rod slidably mounted relative to the power member, a latch device for each of the power and pump rod members and including trip means, and a pin connected therewith for actuation by said endless chain timing device, and means for locking the pin in engagement with one of the cross members, and the latch device for the pump rod member having the pin arrangement to lock said member in holding position while the latch device for the power member is released and the connecting means is disconnected.

10. In a pump rod connecting device, the combination of pump and power rod sections, a connecting section, a base mounting said sections, a pair of shafts journaled on said base, the axis of the respective shafts being in alignment, a chain sprocket mounted on each of said shafts, a chain extending around said sprockets in driving relation, clutch and lever means for rotating said sprockets connecting one of said rod sections for rotation of said sprockets upon reciprocation of said rod section, and slide bolt latch means for connecting one of said pump and power rod sections with the connecting section after a predetermined number of strokes of said power section.
